MANUFACTURE OF GOLF BALLS OR THE
LIKECharles R. Sibley, Marblehead, Mass., assignor to
Sibley-Pym Corporation, Lynn, Mass., a cor-
poration of Massachusetts

Application January 28, 1935, Serial No. 3,773

25 Claims. (Cl. 242—3)

This invention relates to the manufacture of cores for golf balls and other wound articles. In one aspect it consists in a novel process of producing a resilient core by a continuous winding cycle in which thread is laid in different parts of the ball in great circle fashion and in basket weave fashion. In another aspect it consists in a novel machine for carrying out the process of my invention.

In the manufacture of golf balls it has been found that cores may be wound at a high rate of speed when the thread is laid in great circle fashion, that is to say, in courses which correspond substantially to the full or meridian diameter of the core. A number of successful commercial machines operate in this manner, the thread being laid on one full diameter or great circle of the core for one or two turns, and then the axis of rotation of the core being slightly shifted so that the next turns of thread are laid upon another great circle slightly displaced from the preceding turns. The great circle process of winding is not only advantageous from the standpoint of high speed of winding but it also lends itself to winding at relatively high tension, since the thread is thus delivered symmetrically with respect to the core positioning elements and substantially in the plane of maximum driving traction upon the core.

While great circle winding is advantageous in the respects noted, certain manufacturers of golf balls prefer cores in which the elastic thread is laid, at least in the surface windings of the core, in basket weave fashion, that is to say, with substantial spaces between adjacent turns of the thread. In that style of winding the consecutive turns are spaced from each other and need not all be laid in great circle fashion but may be displaced laterally so as to form turns on the core which are less than the full diameter thereof. The basket weave winding gives to the surface of the core a rougher and more open texture and presents interstices into which the plastic material of the shell may enter in the molding operation. A somewhat better bond is, therefore, secured between a basket wound core and the molded shell. This appears so desirable that many manufacturers divide the winding operation into two distinct steps, some going so far as to take the partially wound core from a great circle winding machine and present it to a second winding machine for completing or topping the core with thread laid in basket weave fashion. This procedure, of course, adds greatly to the expense of manufacture and necessitates the extra operations of fastening off the end of the great circle wound thread and fastening in the end of the basket weave wound thread.

I have discovered a process whereby the complete core may be wound by a continuous wind-

ing cycle without interruption and from a continuous elastic thread laid first in great circle fashion and then in basket weave fashion. The process of my invention is characterized by rotating a core continuously first at a high rate of speed in a manner for great circle winding, and then at a lower rate of speed in a manner for basket weave winding, meanwhile delivering elastic thread continuously to the core. In winding the inner portion of the core, I preferably engage the same by members rotatable in fixed axial position, and under these conditions the axis of rotation of the core is shifted gradually and the thread laid in great circle fashion. When the desired predetermined diameter of core has been reached, I impart an additional axial movement to one of the members which rotate and position the core, thus abruptly shifting the axis of rotation of the core between turns so that the thread is wound thereon in basket weave fashion.

Various mechanisms may be employed for carrying out the process of my invention. For purposes of illustration I have herein disclosed a machine in which the core is first rotated and positioned by three members rotatable in fixed axial position, one of said members being adapted to be automatically oscillated in axial movement when it is desired to lay the elastic thread in basket weave fashion. It will be understood that the specific winding machine herein selected for illustration is merely for the purpose of exemplifying one manner in which the process of my invention may be carried out, and that my invention contemplates the continuous winding first in great circle fashion and then in basket weave fashion, or vice versa, by any mechanism suitable for these two functions.

In the accompanying drawings—

Fig. 1 is a view in side elevation of a machine adapted for carrying out my novel process;

Fig. 2 is a view in perspective of the machine as seen from the rear, with the motor parts omitted;

Fig. 3 is a fragmentary view of the core positioning and rotating parts of the machine;

Fig. 4 is a view in side elevation, partly in section and on an enlarged scale, of the rear part of the machine;

Fig. 5 is a view in elevation and on a still larger scale showing a great-circle-wound core in its position in the machine; and

Fig. 6 is a similar view of a basket-weave wound core.

The machine herein illustrated is in some aspects based upon that disclosed in United States Letters Patent No. 2,033,356 granted March 10, 1936, and for details of construction not herein shown reference may be had to that application.

The main frame 10 of the machine has at its forward end a vertical panel 11 which carries the core positioning and rotating mechanism. This includes a roll 13 journaled to rotate freely upon the cylindrical end of a square shaft 12, and a driven roll 15. The square shaft 12 is mounted for horizontal reciprocation in bearings formed in the panel 11 and the driven roll 15 is fast to the forward end of a rotary shaft 39 journaled in bearings provided in the panel 11. The driven roll 15 is concave in contour and the roll 13 is herein shown as being straight sided. Over the two rolls is stretched an endless flexible apron 16, which may be of suitable rubber composition and which serves both to provide a cradle for holding the core 28 and to impart rotation thereto in the winding operation. The apron or band 16 also rotates the roll 13 at all times, both while reciprocating axially and while rotating on a fixed axis.

The core 28 is held firmly in place upon the apron 16 and its supporting rolls by a detector disk 17 having a convex rim and being mounted for free rotation upon a stud projecting from the end of an arm 19. The arm extends transversely across the front of the panel 11 and is secured at its other end to the forward end of the horizontal shaft 20 which is journaled in the panel 11. To the rear end of the shaft 20 is secured a transverse arm 21 which extends across the rear face of the panel 11 and carries an adjustable weight 22. The arm 21 projects forwardly at its free end in an extension 85, which will presently be referred to. The weight 22 insures firm engagement of the detector disk 17 upon the core 28 throughout the winding operation.

Elastic thread 25 to be wound upon the core is supplied from a reel or spool 26 rotatably mounted in a yoke-shaped bracket 27 supported above the panel 11. Thread 25 is led from the supply spool 26 to tension mechanism, not herein shown since it forms no part of the present invention, and then over a guide roll 29 to the core 28, as shown in Fig. 3. As the core 28 is rotated and thread 25 supplied thereto, the detector disk 17 reacts with the last wound turns of thread to displace the core and cause it to remain always spherical in shape, the thread being laid upon the core in great circle fashion. Traction for rotating the core is supplied directly by the flexible apron 16 which cradles the core, as shown in Figs. 5 and 6, although the core is actually supported in position by the driven roll 15 and the idle roll 13.

The machine is driven by a motor 30 supported upon the rear portion of the frame 10 and provided with a shaft 31 carrying a universal joint 32 at its outer end. The forward end of the universal joint 32 is connected to the rear end of a shaft 33, best shown in Fig. 4, which is journaled to rotate in ball bearings 34 mounted in a bracket 35 which is bolted to the frame 10. The shaft 33 is arranged directly behind and in alignment with the shaft 39 which carries the driven roller 15, and interposed between these two aligned shafts 33 and 39 is a short intermediate shaft 36 journaled in ball bearings 37 and supported at its rear end by a smaller set of ball bearings which are received within a sleeve 43 keyed to the forward end of the shaft 33.

The motor 30 may rotate at relatively high speed, for example 3600 R. P. M., and the shaft 33, accordingly, is rotated always at this rate of speed. The intermediate shaft 36 may be driven at the full motor speed directly from the shaft

33 or it may be driven through reducing gear mechanism at a much slower rate of speed, for example 600 R. P. M. The machine is so organized as to drive the intermediate shaft 36 at high speed while the core 28 is being wound in great circle fashion, and to drive the intermediate shaft 36 at low speed through the reducing gear mechanism when the core 28 is being wound in basket weave fashion.

The driving mechanism between the shafts 33 and 36 will now be described. As already stated, the shaft 33 carries at its forward end a sleeve or collar 43 which is keyed thereon. Keyed to the sleeve 43 for longitudinal movement thereon is a clutch member 42 having concave clutch surfaces upon both faces. The outer face of the clutch member 42 is arranged to cooperate with a clutch cone 44 fast upon the rear end of the shaft 36. The rear face of the clutch member 42 is arranged to cooperate with a clutch cone 41 which is fast with a pinion 40 upon a sleeve journaled to rotate freely upon the shaft 33. Accordingly, when the clutch member 42 is shifted toward the rear, as shown in Fig. 4, it engages with the clutch cone 41 and acts to drive the pinion 40 at the speed of the shaft 33. While so engaged, the clutch cone 44 is free so that there is no direct driving connection between the shafts 33 and 36.

The pinion 40 is arranged to mesh at all times with a large gear 50 fast upon a shaft journaled to rotate freely in bearings 51 carried by an adjustable bracket 53 which is bolted to the bracket 35 of the frame. On the same shaft with the gear 50 is a smaller gear 52 which meshes at all times with a gear 54 fast upon the rear end of a horizontal shaft 55 journaled in bearings 56 formed in the bracket 38 and carrying at its forward end another gear 57. The gear 57 is arranged to mesh with a pinion 58 which is keyed together with a clutch cone 60 upon a sleeve 59 arranged to rotate freely upon the shaft 36. The clutch cone 60 is arranged to cooperate with a sliding clutch member 61 keyed to the shaft 36 for longitudinal movement thereon and arranged to transmit rotation of the pinion 58 to the shaft 36 when moved rearwardly, as shown in Fig. 4.

The clutch members 42 and 61 are arranged to be shifted simultaneously by shifting mechanism which will now be described. The clutch member 42 is circumferentially grooved to receive a shipper shoe 62 and the clutch member 61 is correspondingly grooved to receive a shipper shoe 63. These shoes extend circumferentially in the grooves of the clutch members and are connected by a yoke-shaped carrier 64 which is supported in position between the arms of a forked shipper lever 65 pivotally mounted upon a fulcrum pin 66 in the bracket 38. At its lower end the shipper lever 65 is connected through an adjustable link 68 to a downwardly extending arm 69 loose to a transverse shaft 70 journaled in the machine frame. The shaft 70 also carries a forwardly extending handle 71 by which the operator may control the position of the shipper lever 65 in certain respects. A tension spring 72 secured to the lower end of the shipper lever tends always to swing the lever in a counter-clockwise direction, as seen in Fig. 1, and to shift the clutch members 42 and 61 into the position shown in Fig. 4, that is to say, to render the reducing gear mechanism effective. Under these conditions it will be seen that the shaft 36 is driven at reduced speed by the clutch cone 60, this in turn being rotated by the gear train

58—57—54—52—50—40. The gear train in turn is rotated by the clutch cone 41 set in motion by the clutch member 42. On the contrary, when the shipper lever 65 is rocked in a clockwise direction against the tension of the spring 72, the clutch cones 42 and 60 are disengaged and the shaft 36 is rotated directly at high speed by the engagement of the clutch member 42 with the clutch cone 44.

The arm 69 above referred to carries a downwardly extending spring blade 73 having at its lower end a hardened wear piece 74. This is arranged to cooperate with a latch block 75 adjustably secured to a latch lever 76 mounted to rock about a fulcrum pin 77 which is carried by a standard projecting from the base of the machine frame. A tension spring 78 is connected to the rear end of the latch lever 76 and tends always to rock it in a clockwise direction. The upper end of the spring 78 is secured to an eye carried by the adjustable link 68. A downwardly extending T-shaped arm 90 is secured to the shaft 70. Its rearwardly extending branch is connected to the forward end of the latch lever 76 by means of a slotted link 91 and its forward end is located in line with the wear piece 74. Consequently, when the handle 71 is depressed, the arm 69 is swung in a clockwise direction and the shipper lever 65 is rocked in a clockwise direction by the link 68 against the tension of the spring 72. When the wear piece 74 has been carried behind the rear upper edge of the latch block 75, the latch lever snaps upwardly under the actuation of the spring 78 and the shipper lever 75 is thus latched in high speed position, that is to say, with the clutch member 42 engaged with the clutch cone 44 and the clutch member 61 disengaged from the clutch cone 60. Under these conditions the winding operation proceeds at high speed in great circle fashion, laying the turns of elastic thread in the manner indicated in Fig. 5.

The depression of the handle 71 is effected by the operator preliminarily to starting the machine and after the mechanism has been once organized to operate in this manner it continues until the latch is tripped either manually at the option of the operator or automatically when the core has reached a predetermined diameter. The latch may be tripped manually at any time by lifting the handle 71, and when this occurs the latch lever 76 is rocked in a counterclockwise direction by the link 91. It will be apparent that the slot in the link 91 permits the arm 90 to be moved rearwardly sufficiently to cause latching engagement between the wear piece 74 and the latch block 75 without affecting the position of the latch lever 76 or in any way preventing it from snapping upwardly in effecting the latching operation.

The latch may be tripped automatically by mechanism which will now be described. The forward end of the latch lever 76 is connected to the lower end of a long vertically-disposed link 79 and the latter is connected at its upper end to a forwardly-extending arm 80 of a yoke member arranged to rock about a transverse shaft 81 which is supported by a lug extending rearwardly from the panel 11, as shown in Fig. 2. The other arm 82 of the yoke carries an adjustable stop member 83 which extends a variable distance beneath the arm 82 and in alignment with a forward extension 85 at the free end of the lever 21. The lever 21, as already explained, carries an adjustable counterweight 22 and tends

always to move downwardly to a position determined by the engagement of the detector disk 17 with the core being wound. The initial position of the arm 82, and consequently of the link 79, is determined by an adjustable stop screw 84 which projects downwardly from the arm 82 and engages the portion of the machine frame which carries the fulcrum pin 81.

From the foregoing description it will be clear that as the diameter of the core increases and the arm 19 is rocked upwardly carrying with it the arm 21, the extension 85 of this arm will engage the stop member 83, rocking the yoke in a counterclockwise direction, lifting the link 79 and rocking the latch lever 76 downwardly at its rear end so as to disengage the latch block 75 from the wear piece 74 and thus permit the spring 72 to shift the speed reducing mechanism to its low speed condition.

Whenever the machine is shifted from high to low speed operation, mechanism for oscillating the square shaft 12 and the idle roll 13 is thrown into action. This mechanism will now be described. The shaft 12 is connected at its rear end to an oscillatory arm 92 slotted at its lower end to receive a fulcrum pin 93. The fulcrum pin is carried by an adjustable arm 94 which is slotted and clamped to the machine frame. The amplitude of movement of the arm 92 may be varied and adjusted by shifting the position of the arm 34 and the fulcrum pin 93. The oscillatory arm 92 is connected through an adjustable link 95 to the free end of a cam lever 96 which is pivotally supported at a point (not shown) behind the shaft 22, as seen in Fig. 3, and is provided with a cam roll 97 arranged to run in the track of a cam 98 loosely mounted on the forward end of the shaft 55.

A toothed clutch is provided for engaging and disengaging the cam 98 with respect to the shaft 55. To this end the forward face of the cam is provided with teeth 100 arranged to interlock with corresponding teeth of a member 101 keyed to the shaft 105 but free to move longitudinally thereon. The member 101 is provided with a circumferential groove to receive the pins of a horizontally moving shipper yoke 102. The shipper member 102 has a pin and slot connection with a vertically-extending arm 103 which is pivotally supported at its upper end upon the pivot shaft 81, already described, and has a yoke-shaped portion through which passes the shaft 39. A forwardly-extending tension spring 104 connected to the lower end of the arm 103 tends always to swing it forwardly and through the shipper 102 to disengage the clutch 100—101.

A self-contained clutch 106 is interposed between the shaft 36 of the driving mechanism of the machine and the shaft 39 which operates the instrumentalities of the machine handling the core. The clutch 106 is not herein shown in full detail since it corresponds to that fully disclosed in said Letters Patent No. 2,033,356. The clutch 106 is normally disengaged and is engaged by movement of the sleeve 107 under the actuation of the arm 103, which is provided with pins 108 for connection with a groove in the sleeve 107. When the arm 103 is rocked rearwardly, both the clutch 106 and the clutch 100—101 are engaged. Accordingly, the core being wound is set in rotation and an operative connection is established between the low speed mechanism and the connections for oscillating the square shaft 12. If the slow speed mechanism has been thrown into operation, the shaft 12 is reciprocated and oscil-

latory movement imparted to the core in addition to its rotary movement. If, however, the driving mechanism is operating at high speed, the shaft oscillating mechanism still remains at rest.

5. The arm 103 is connected through a rod 109 to a starting button 105 located within convenient reach of the operator, who may start the winding operation by pushing the starting button 105 inwardly and rocking the arm 103 rearwardly against the tension of the spring 104. When this occurs, the arm 104 is latched in running position by a latch, not shown, and this in turn may be tripped when it is desired to stop the machine by depressing a stopping button 110. The details of 10 this mechanism are not herein illustrated since they form no part of the present invention and are fully disclosed in the pending application 15 above identified.

The machine above described has of itself 20 many novel features of construction but it exemplifies only one suitable type of machine for carrying out the novel method of my invention, and it will be understood that widely different mechanism may be employed for carrying out 25 the method. Bearing in mind that the illustrated machine is only one example of what might be used, the method of handling the core therein will be summarized as carried out under commercial conditions. The operator starts with a 30 center, which may be solid rubber or a liquid-filled ball, and upon this makes a few turns of elastic thread 25. He then lifts the detector disk 17 and places the core upon the apron 16 between the rolls 13 and 15, the thread 25 running to the core 28 from suitable tension mechanism, not herein described. Meanwhile, the 35 motor 30 is running and the handle 71 has been depressed, disengaging the clutch member 42 from the cone 41 and engaging it with the cone 44, so that the reducing gear mechanism is at rest 40 and the shaft 36 is rotating at high speed. The operator now depresses the starting button 105, clutching the shaft 39 to the high speed shaft 36 and incidentally engaging the clutch 100—101, 45 although, as already explained, the shaft 55 is at this time at rest. Immediately upon the engagement of the clutch 106, the driven roll 15 revolves at high speed, driving the apron 16 and rotating the core 28 beneath the detector disk 17. Under these conditions, the thread is laid 50 upon the core 28 in great circle fashion, the core being gradually displaced by the reaction of the detector disk with the last wound turns of thread but the successive turns being laid close together 55 at high speed, rapidly building up a spherical core of smooth exterior. As the winding operation progresses and the diameter of the core 28 increases, the detector disk is lifted, carrying with it the arm 21, which eventually engages the stop member 83 and trips the latch 74—75, permitting 60 the spring 72 to throw the reducing gear mechanism into operation and reduce the speed of rotation of the roll 15 from approximately 3600 to 600 R. P. M.

65 When the shaft 55 of the reducing gear mechanism starts to rotate, the cam 98 at once becomes effective to oscillate the vertical arm 92 and impart a reciprocation to the square shaft 12 and the roll 13 carried thereby. The effect of this 70 movement is to impart a pronounced oscillation to the core 28 in a direction transverse to its direction of rotation, with the result that the successive turns of elastic thread are laid upon the core with a wide spacing, giving the desired basket 75 weave effect to the surface of the core. The

winding operation continues in this fashion until the core has increased in size to the desired diameter or until the operator has stopped the machine by depressing the stopping button 110 and releasing the clutch arm 103. Preferably, the machine is provided with automatic stopping mechanism arranged to be tripped when the detector arm 19 has been lifted to a predetermined but adjustable point. Such mechanism is disclosed in the Letters Patent No. 2,033,356 above identified but is not herein shown. Upon the stopping of the machine, either automatically or by the operator, the completed core may be removed, the loose end of thread fastened off and the golf ball completely by the application of a molded shell, as will be well understood.

Having thus described my invention, what I claim as new and desire to secure by Letters Patent is:

1. Process of manufacturing golf balls or the like by a continuous winding cycle, characterized by the delivery of a continuous elastic thread to a core, rotating the core at a high rate of uniform peripheral speed in laying the inner turns of thread thereon, reducing the peripheral speed of the core while maintaining it in substantially the same position, and laying the outer turns of the same thread in basket weave fashion at the reduced winding speed.

2. Process of manufacturing golf balls or the like by a continuous winding cycle, characterized by the delivery of a continuous elastic thread to a core rotating first at one speed and then at a different speed, and varying the rate of axial displacement of the core simultaneously with such changes in speed.

3. Process of manufacturing golf balls or the like by a continuous winding cycle, characterized by the delivery of an elastic thread to a core rotating continuously first at high and then at low speeds, and causing pronounced axial displacements of the core to take place after subjecting the core to such change from high speed rotation.

4. Process of manufacturing golf balls or the like by a continuous winding cycle, characterized by the delivery of an elastic thread continuously to a core rotating first at high speed with gradual axial displacement and then at low speed while external impulses in a circumferential direction are imparted thereto to cause a succession of more abrupt axial displacements of the core being wound.

5. Process of manufacturing golf balls or the like by a continuous winding cycle, characterized by the delivery of a continuous elastic thread to a core rotating first at high speed under uniform conditions tending circumferentially to displace the core being wound and then at a lower speed while a succession of circumferential impulses is imparted to the core at a predetermined rate.

6. Process of manufacturing golf balls or the like by a continuous winding cycle, which consists in rotating a core continuously, first at a high rate of speed for great circle winding and then at a low rate of speed for basket weave winding, and delivering elastic thread continuously to the core throughout the entire cycle.

7. Process of manufacturing golf balls or the like by a continuous winding cycle, which consists in delivering an elastic thread to a core, rotating the core continuously first with a gradual shifting of its axis of rotation whereby the thread is wound in a great circle manner and then with abrupt periodic shifting of its axis of rotation

whereby the thread is wound in basket weave fashion.

8. Process of manufacturing golf balls or the like by a continuous winding cycle, characterized by the delivery of a continuous elastic thread to a core rotated at high uniform peripheral speed while its axis of rotation is gradually and uniformly displaced, the core being thereafter rotated at lower speed and having its axis of rotation intermittently displaced by external impulses occurring intermittently in opposite directions.

9. A machine for winding golf balls or the like, comprising three core-positioning members arranged to rotate in fixed axial position, and means under the control of the operator for imparting axial movement to one of said members during a portion of the winding cycle.

10. A machine for winding golf balls or the like, comprising a pair of core-supporting rolls, and automatic mechanism for imparting axial reciprocation to one of them when the core reaches a predetermined diameter.

11. A machine for winding golf balls or the like, comprising a pair of core-supporting rolls, means for driving one of said rolls first at one speed and then a different speed, and means for imparting an oscillating movement to one roll when such change of speed is effected and thereafter during the slow speed rotation of the roll.

12. A machine for winding golf balls or the like by a continuous winding cycle, comprising a pair of parallel shafts having rollers located side by side for supporting a core, means for driving one of said rollers at different rates of speed, and means for axially oscillating the other roller during certain periods in the winding cycle, said means being arranged for holding the said other roll against axial movement during certain periods of the winding cycle.

13. A machine for winding golf balls or the like, comprising a pair of parallel shafts having rollers located side by side for supporting a core, two-speed mechanism for driving one roller at either high or low speed, and mechanism for oscillating the other roller arranged to be rendered inoperative while the driven roller is rotating at high speed.

14. A machine for winding golf balls or the like, comprising a high speed shaft, low speed driving mechanism, a core-turning roller associated with said shaft and said mechanism, a clutch for engaging or disengaging said shaft and roller, an idle core-supporting roll, and mechanism for oscillating the same arranged to be thrown into or out of action as said clutch is engaged or disengaged.

15. A machine for winding golf ball cores by a continuous winding cycle, comprising cooperating core-supporting rolls, a rotary shaft carrying one roll, means for driving said shaft at two different speeds, means controlled by the diameter of the core for determining the speed of said shaft, a reciprocating shaft for the other of said core-supporting rolls, and means for governing the period of reciprocation of said latter shaft in the winding cycle.

16. A machine for winding golf ball cores, comprising a rotary shaft carrying a core-supporting roll, a non-rotary reciprocating shaft carrying a cooperating core supporting roll, means for driving the rotary shaft at one of two speeds depending upon the diameter of the core in process of being wound, and means for reciprocating said

non-rotary shaft only during the rotation of said rotary shaft at its lower speed.

17. A machine for winding cores, having cooperating rotary core-supporting rolls, two-speed mechanism for rotating one of said rolls at different rates of speed, and means for imparting an endwise reciprocation to one of said rolls arranged to be thrown into or out of action when the speed of said rotary roll is changed from one rate to another and having provision for varying the amplitude of such reciprocation.

18. A machine for winding golf ball cores or the like, comprising instrumentalities for positioning and rotating a core to be wound, driving mechanism for certain of said instrumentalities constructed and arranged to operate them at either of two predetermined rates of speed while the winding operation progresses continuously, and automatic means for effecting such change of speed without interrupting the operation of the driving mechanism.

19. A machine for winding golf ball cores or the like, having means for supporting and turning the core to be wound comprising a positively driven roll, a roll supported for free rotation, and means for axially reciprocating the freely rotatable roll.

20. A machine for winding golf balls or the like, including a driven shaft having a roll fast thereon, a parallel shaft having a roll mounted for free rotation and for longitudinal reciprocation, and an endless band arranged to cradle the core to be wound between the two rolls and to rotate said freely rotatable roll while it is reciprocating.

21. A machine for winding golf balls or the like, including spaced parallel shafts, one having an inwardly concave roll and the other a cylindrical roll, an endless belt driven by said inwardly concave roll and driving said cylindrical roll and cradling the core to be wound between the two, and means for reciprocating said cylindrical roll.

22. A machine for winding golf balls or the like, including spaced horizontal shafts, one being driven and having a roll fast thereon, and the other carrying a longitudinally reciprocating roll mounted thereon for free rotation, and an endless elastic band passing about said rolls and serving both to rotate the reciprocating roll and to exert traction on a core supported between the rolls.

23. A machine for winding golf balls or the like, comprising a driven shaft having a roll fast thereon, an adjacent shaft carrying an axially reciprocating roll mounted thereon for free rotation, a hold-down roll mounted above and between said rolls, and an endless elastic band passing about the roll on the driven shaft, driving the reciprocating roll and cradling the core to be wound beneath said hold-down roll.

24. A machine for winding golf balls or the like comprising a pair of spaced core-supporting rolls, an endless elastic apron running upon said rolls, and means for imparting to the core-engaging portion of the apron a combined longitudinal and transverse movement.

25. A machine for winding golf balls or the like, comprising a pair of spaced rolls for supporting and rotating a core to be wound, means for driving one of said rolls, a flexible band for driving the other roll from said driven roll, and means for reciprocating said other roll within the band.

CHARLES R. SIBLEY.
